LEHR

Constantine W. Kulig, Hartford, Conn., assignor
to Emhart Manufacturing Company, Hartford,
Conn., a corporation of Delaware

Application April 14, 1951, Serial No. 221,087

3 Claims. (Cl. 49—47)

1

The present invention relates to improvements in apparatus for annealing glassware and more particularly to an improvement in the construction and operation of the glassware annealing lehr described in the copending application Serial No. 219,685 filed April 6, 1951, by D. G. Merrill in which the temperature gradient through the entire annealing cycle is controlled by automatically regulating longitudinal drift of atmosphere through the lehr.

In the operation of the lehr described in the Merrill application, ware is passed through an elongated lehr tunnel which includes conditioning, slow cooling and fast cooling zones. Heat is supplied to the tunnel solely in the conditioning zone and heated atmosphere is withdrawn by a fan or blower from the rear end of the slow cooling zone at a constant rate preselected by throttling dampers. If the temperature in the conditioning zone is low, a portion or all of the withdrawn atmosphere is reintroduced into the conditioning zone and recirculated to the blower.

For best fuel economy with less than maximum loads, only a relatively small percentage of the recirculating fan capacity is required for operation. Since the recirculating fan operates at constant speed, recirculating air dampers are set to throttle the air handled by the fan to a desired percentage of its capacity. Within this relatively small amount of recirculating air, a desirable cooling rate beyond the annealing or slow cooling zone or section is obtained for all but maximum loads. However, for maximum loads, the cooling rate beyond the annealing section has to be increased.

This may be accomplished by opening the recirculating dampers further and drawing air from the slow cooling zone, thereby effecting a greater forward drift beyond the slow cooling or annealing zone.

The present invention automatically provides for the small amount of recirculating air required for best fuel economy at light loads and for automatically increasing the amount of recirculating air and drawing more cooling air from between the forced cooling and the annealing zones for heavier loads.

More particularly, the invention provides automatic mechanism responsive to lehr temperature for operating control dampers which throttle the heated air withdrawn from the back of the annealing or slow cooling zone and for simultaneously operating other control means, as for example, dampers which regulate the portion of the withdrawn air reintroduced into the tunnel and the portion not reintroduced.

2

In the hereinafter described illustrative embodiment of the invention, the portion not reintroduced is directed into a preheater for the conveyor belt which transports ware through the tunnel thereby increasing the heat economy of the lehr.

Other advantages will be pointed out or become apparent from the description of the portion of a lehr shown in the accompanying drawings in which a preferred form of the invention is incorporated and in which:

Fig. 1 is a side elevation view of the conditioning or heating section of a lehr, the wall of which has been partially broken away to show dampers and their controls for regulating the distribution of heated tunnel air in accordance with the invention.

Fig. 2 is a cross-sectional view taken on line 2—2 of Fig. 1 and showing damper and damper operating mechanism at the top of the lehr; and

Fig. 3 is an enlarged fragmentary view of a portion of the damper control mechanism broken away from the Fig. 1 view.

Referring to the drawings, a firebox or heating and conditioning section 1 of a lehr is shown. The remainder of the lehr is a cooling section which is shown fragmentarily and is generally designated 2. Details of the cooling section or portion 2 of the lehr are not critical to the invention and may take a variety of forms. A preferred construction is shown and described in the aforementioned Merrill application and includes a slow cooling tunnel zone in which glassware is annealed and which is followed by a more rapid cooling tunnel zone in which to prepare the ware for handling.

The firebox or conditioning section 1 includes a suitable frame structure generally designated 3, which forms the front section of a tunnel 4 which extends the length of the lehr and through which ware is transported by an endless belt conveyor 5. A fully muffed combustion chamber 7 is located beneath the belt 5 and contains a burner block 6 and gaseous combustion products from which are directed through a horizontal baffled passage in the chamber 7 and out through ducts or stacks 8 and 9.

After fuel is ignited at the burner 6, its combustion is completed in the chamber 7 forward of a first baffle 1a which divides and directs the combustion gases through passageways which are at opposite sides of the lehr and which are baffled as at 1b so as to assure maximum heat extraction from the gases before they pass through the two up-take vents 8 and 9. Independently controlled ejectors 8a and 9a and a

suitable blower, such as is shown mounted on the top of the firebox section (Fig. 1), may be provided at the top of the up-takes for the necessary draft to draw the gases from the chamber 7 and for regulating the portions of heat distributed to the opposite sides of the tunnel.

The combustion chamber 7 is enclosed both above and below and at its ends with highly conductive tile 10 which provides for a maximum transfer of heat directly to the air in the tunnel 4 and to air in a passageway 11 beneath the tiles 10.

Air is supplied to the passageway 11 and to a belt preheater 12 from a pair of downcomers 13 and 14 which are disposed about the uptakes 8 and 9, respectively. The heated air in the passageway 11 is directed upwardly through a vertical passageway 15 into the front end of the tunnel 4.

The belt warmer 12 beneath the firebox 1 provides an enclosed passageway 16 through which the endless belt conveyor 5 returns to the front end of the lehr and into which the air from the downcomers 13 and 14 is discharged in predetermined amounts regulated by a damper 17. The damper 17 is automatically preset by suitable linkage, generally designated 18, which connects the damper with an air motor 19 that operates in response to changes in temperature of a thermostatic element 20 located at the top and adjacent the front end of the tunnel 4.

As shown in Fig. 1, the linkage 18 includes a connecting rod 18a between the motor 19 and an arm 21a of a bell crank 21; another arm 21b of which is connected by rod 22 with a crank 23 secured to a shaft 24 on which the damper 17 is mounted.

A recirculating blower or similar device B withdraws and directs air from the rear end of the annealing or slow cooling zone of the tunnel through ducts or flues 13a and 14a to the downcomers 13 and 14, respectively, for introduction into the belt preheater 12 and reintroduction into the tunnel 4 at the front of the firebox section through the passages 11 and 15.

As shown in the drawings, the flues 13a and 14a are each provided with a damper 25 for throttling the rate at which air is withdrawn from the tunnel and discharged into the downcomers 13 and 14. Both dampers 25 are secured to a rotatable shaft 26 which extends transversely through the lehr and which has secured to an end thereof a crank 27 by means of which the positions of the dampers are adjusted automatically between the relatively closed or throttled position shown in dotted line in Fig. 3 and the more open position shown in phantom.

The crank 27 normally is maintained by a spring 28 against an adjustable stop 29 which limits clockwise movement of the crank and determines the normal throttled positions of the dampers 25. As shown in Fig. 3, the stop 29 is slotted as at 29a and provided with a fastener 29b by means of which the position of the stop 29 may be adjusted in conventional manner. Opening of the dampers is effected by the bell crank 21 to an arm 21c of which is connected a rod 30 having an adjustable lost motion connection with the crank 27. The lost motion connection is provided with an ear 27a of the crank 27 through which the rod 30 slidably extends, the ear 27 being engageable by nuts 31 to pivot the crank 27 counterclockwise to further open the dampers 25 whenever the bell crank 21 pivots sufficiently in the clockwise direction in response

to increase in the temperature of the thermostat 20 which is located just inside the front entrance.

The temperature in the firebox portion of the tunnel is primarily controlled by a thermostat 32 which regulates the burner 6.

In accordance with the present invention, the amount of air returned through the ducts 13a and 14a is regulated automatically by the dampers 25 which are adjusted in direct response to changes in the temperature of the thermostat 20 and indirectly in response to indraft or outdraft at the entrance to the lehr. The tendency for outdraft at the lehr entrance is caused by increased forward drift which increases the temperature of the thermostat 20. Indraft at the lehr entrance is caused by backward drift which brings cold air into the tunnel entrance and lowers the temperature of the thermostat 20.

The front entrance control also responds indirectly to load changes. These responses are as follows: with light load or an empty lehr, the temperature at 20 is low so that the dampers 17 and 25 are automatically adjusted by the motor 19 to return a minimum volume of air through the ducts 13a and 14a virtually all of which is reheated in the passage 11 and reintroduced into the tunnel. With light to moderate loads, the damper 25 is not moved and the volume of air withdrawn from the tunnel remains minimal, but a lesser portion is reheated in the space 11, the damper 17 automatically being moved to direct a greater portion into the belt preheater 12.

With moderate to heavy loads, as, for example, above 350 oz. per minute in a 64 ft. x 5 ft. wide lehr, the dampers 25 are opened further and the returned air volume is increased to a maximum virtually all of which is diverted to the belt preheater 12.

These provisions insure adequate heat for the annealing zone, minimum loss through heating of excess air, maximum cooling capacity, and maximum heat recovery through belt preheating and recirculation.

The maximum backward drift occurs in the tunnel 4 when the lehr is empty. This drift is a flow of air in definite amount from the conditioning zone to the rear of the slow cooling zone which cools and gives up the amount of heat needed to balance wall losses.

In order to maintain a neutral flow at the front door with an empty lehr, the amount of heated air returned through the ducts 13a and 14a for recirculating is just sufficient to effect the necessary backward drift from the conditioning to the slow cooling zone while maintaining a neutral drift or flow at the entrance to the tunnel and beyond the slow cooling zone.

With a light load of glass, the required backward drift in the slow cooling zone diminishes, but the ducts 13a and 14a continue to return the same volume of heated air. However, the thermostat 20 operates to divert some of the air to the belt preheater 12 so that the air heated in the passage 11 under the firebox 1 is only that necessary to supply the diminished tunnel drift and keep a neutral drift at the front door. The amount of air used for belt heating is supplied by forward drift from beyond the slow cooling zone to the blower B and in effect heat supplied to the belt preheater is that recovered from air from the rapid cooling zone.

With a fairly heavy load, the tunnel drift becomes all forward and the thermostat 20 acts to adjust the damper 17 so that a maximum

amount of returned air is directed into the belt preheater 12 and a minimum amount is heated in the chamber 11 and reintroduced into the tunnel. Simultaneously, in accordance with the invention, the thermostat and its associated motor 19 act through rod 30 and its lost motion connection with the crank 27 to adjust the dampers 25 to their maximum open positions so that the amount of air returned through the ducts 13a and 14a is increased to a maximum.

Having thus described my invention, I claim:

1. In a glassware annealing tunnel lehr having a heating and conditioning section and a cooling section which provide conditioning and cooling zones of the tunnel through which ware is transported, means for withdrawing atmosphere from the cooling zone of said tunnel and directing the withdrawn atmosphere to the conditioning section of the lehr, means for dividing said withdrawn atmosphere and reintroducing a portion only of the withdrawn atmosphere into the conditioning zone of the tunnel, and discharging another portion out of the lehr, and means for automatically regulating the quantity of withdrawn atmosphere, said regulating means being responsive to lehr temperature in the conditioning zone.

2. In a glassware annealing tunnel lehr having a heating and conditioning section and a cooling section which provide conditioning and cooling zones of the tunnel through which ware is transported, means for withdrawing atmosphere from the cooling zone of said tunnel and directing the withdrawn atmosphere to the conditioning section of the lehr, means for dividing said withdrawn atmosphere and reintroducing a portion only of the withdrawn atmosphere into the conditioning zone of the tunnel and discharging another portion out of the lehr, means for regulating the quantity of atmosphere withdrawn,

means for regulating the portion of withdrawn atmosphere reintroduced into the conditioning zone of the tunnel relative to said portion discharged from the lehr, and thermostatic means responsive to lehr temperature in the conditioning zone for automatically adjusting both of said regulating means.

3. In a glassware annealing tunnel lehr having a heating and conditioning section and a cooling section which provide conditioning and cooling zones of the tunnel through which ware is transported on an endless belt conveyor, a warmer for heating the belt outside of the tunnel, means for withdrawing atmosphere from the cooling zone of said tunnel and directing the withdrawn atmosphere to the conditioning section of the lehr, means for dividing said withdrawn atmosphere and directing a portion of said withdrawn atmosphere into the belt warmer and another portion of said withdrawn atmosphere into the conditioning zone within the tunnel, damper means for regulating the quantity of air withdrawn, damper means for regulating the proportion of returned atmosphere discharged into the conditioning zone of the tunnel and into the belt warmer independently of the quantity regulating damper means, and thermostatic means responsive to the temperature of the atmosphere in the conditioning zone for automatically adjusting said damper means.
